UNITED STATES PATENT OFFICE

PHILLIP MORGAN, OF STOCKTON, CALIFORNIA

GAS MIXING DEVICE

Application filed June 17, 1929. Serial No. 371,455.

This invention relates to improvements in gasoline mixing devices and has particular reference to means for increasing the amount of air which is delivered to the carburetor after the engine has become warmed.

Another object of the invention is to produce a device which may be inserted between the usual carburetor and the usual manifold without altering the construction there-
10 of.

A further object is to provide means where by volatile gas is withdrawn from the crank case.

A still further object is to produce a de-
15 vice which is economical to manufacture.

Other objects and advantages will be ap-
parent during the course of the following
description.

In the accompanying drawings forming
20 a part of this specification and in which
like numerals are employed to designate like
parts throughout the same,

Figure 1 is a fragmentary view of an in-
25 ternal combustion engine having my inven-
tion applied thereto,

Figure 2 is a bottom plan view of my de-
vice,

Figure 3 is a top plan view of my device,

Figure 4 is a side elevation of the mixture
30 plate, and

Figure 5 is a top plan view thereto.

It is a well known fact that after a vehicle
35 is running and the engine is warmed, it is
possible to increase the amount of air de-
livered to the carburetor and thereby cause
a greater efficiency of operation. Applicant
has devised a means whereby the warm vola-
tile gas and air contained within the crank
case of the motor may be utilized for this
40 purpose and he has therefore devised a
structure which is simple and one which will
function in the manner described.

In the accompanying drawings wherein
45 for the purpose of illustration is shown a
preferred embodiment of my invention, the
numeral 5 designates the crank case of a
motor having cylinders 6 and an intake
manifold 7. This intake manifold is con-
nected by the usual down-pipe 8 having a
50 flange 9 to a carburetor 11 having a flange

12. It is between the flanges 9 and 12 that
I insert my invention, which consists of the
plate 13 of the same general shape as the
flanges 9 and 12 and adapted to be bolted
theretwixen by the bolts 14 and 16. The 55
plate 13 has a semi-circular groove 17 formed
upon its undersurface as best shown in
Figure 2. This groove is connected to a
pipe 18 the purpose of which will be later
seen. The groove 17 connects with a groove 60
19 formed on the upper surface of the plate
13 through the medium of ports 21 and 22.
From the groove 19 to the central bore 23, I
provide radial passages 24. These passages
permit the air coming from the pipe 18 to 65
pass from the groove 17 to the ports 21 and
22 to the groove 19 thence through the radial
passages, to the interior or bore 23 where it
will join in with the flow of carbureted air
coming from the carburetor. 70

In order to form a more perfect mixture
I provide a plate 26 which has a plurality
of upstanding vanes 27 positioned thereon,
which vanes serve to give a whirling motion
to the air passing therethrough. This plate 75
36 is bolted between plate 13 and the flange
of the carburetor. A pipe 18 is connected to
a pipe 28 which in turn connects to a casing
29 having a valve positioned therein. This
valve is actuated through the medium of a 80
lever 31 and a rod 32. A pipe 33 extends
from the valve casing 29 to the engine crank
case 5. The result is that when the operator
actuates the valve through the lever 31 air
will be admitted from the crank case 85
through the pipe 33, valve housing 29, pipe
28, pipe 18, to the groove 17 from which
point the course has been previously traced.

It will thus be seen that I have produced
a device which will accomplish all the ob-
jects above set forth. 90

It is to be understood that the form of my
invention herewith shown and described is
to be taken as a preferred example of the 95
same and that various changes relative to
the material, size, shape and arrangement of
parts may be resorted to without departing
from the spirit of the invention or the scope
of the subjoined claim. 100

Having thus described my invention, I
claim:—

In a device of the character described, a
plate having a central bore formed therein,
a groove formed upon one side of said plate
5 and concentric with said bore, a groove
formed upon the opposite side of said plate
passages extending between said grooves,
said second groove being concentric with
said bore, passages connecting said second
10 mentioned groove and said central bore, and
means for delivering air to said grooves.

In testimony whereof I affix my signaturē.

PHILLIP MORGAN.
